UNITED STATES PATENT OFFICE

110,062

DESIGN FOR A DRESS ENSEMBLE

Ruth Williams, Chicago, Ill., assignor to Samuel Reich, Chicago, Ill.

Application March 28, 1938, Serial No. 76,140

Term of patent 3½ years

To all whom it may concern:

Be it known that I, Ruth Williams, a citizen of the United States, residing at Chicago, in the county of Cook and State of Illinois, have invented a new, original, and ornamental Design for a Dress Ensemble, of which the following is a specification, reference being had to the accompanying drawing, forming a part thereof.

Fig. 1 is a front view of a dress ensemble showing my design;

Fig. 2 is a rear view of the ensemble shown in Fig. 1;

Fig. 3 is a front view of the dress section of the ensemble shown in Fig. 1;

Fig. 4 is a rear view of Fig. 3; and

Fig. 5 is an enlarged fragmentary view of the dress section illustrating the double collar feature.

The characteristic feature of my design resides in the combination on the ensemble disclosed of the cape portion having tuxedo revers, a contrastingly colored collar, seamed shoulders, and a plain back in association with the double collared dress as shown.

I claim:

The ornamental design for a dress ensemble substantially as shown and described.

RUTH WILLIAMS.
